(57) **CLAIM**

The ornamental design for an all terrain vehicle, as shown and described.

DESCRIPTION

FIG. 1 is a front perspective view of an all terrain vehicle in accordance with the present disclosure;

FIG. 2 is a rear perspective view thereof;

FIG. 3 is a top perspective view thereof;

FIG. 4 is a bottom perspective view thereof;

FIG. 5 is a right side perspective view thereof;

FIG. 6 is a left side perspective view thereof;

FIG. 7 is a front and right side perspective view thereof; and,

FIG. 8 is a rear and left side perspective view thereof.

In the drawings, the light and shade shown on the surfaces represents the contours of the three-dimensional surfaces.
